ELECTRIC CHIME DEVICE

Gisbert L. Bossard, Cleveland, Ohio

Application September 28, 1946, Serial No. 700,133

6 Claims. (Cl. 177—7)

1

This invention relates to a signal device, particularly of the type comprising an electromagnetically actuated chime.

It is the object of the invention to so construct a signal device of this character as to facilitate the assembly and mounting thereof with the consequent reduction in cost, but more particularly to improve upon the tone quality and volume.

One feature of the invention resides in the mounting of the actuating unit whereby the entire operative structure is carried directly upon the front housing cover as distinguished from the usual support thereof upon the side walls or back plate. This is accomplished by providing the housing cover with inwardly extending bosses to which the operative structure may be directly and readily secured as hereinafter described.

A further feature of the invention resides in the provision of a series of vibration emitting apertures formed in the side walls of the housing cover, which comprises a resonator chamber, in such relation to the respective tonal bars as to minimize any dampening effect thereon and eliminate the necessity of accurate tuning of the bars with respect to said chamber. Thus, the desired resonance is obtained with improved tone quality and reduced dampening effect, as well as increased volume by mounting the tonal bars in centered spaced relation to the multiapertured walls of the resonance chamber.

A further feature of the invention resides in the provision of a dust cover of insulating material removably secured over the back of the housing cover for enclosing the resonance chamber and sealing the operative structure therein, but wherein said back cover is apertured to expose a terminal plate for convenient wiring without opening up the chamber. This avoids the possibility of bunching wires during installation inside the resonance chamber and against the tonal bars, completely insulating said wiring from the resonance chamber and operative structure therein.

A further feature of the invention resides in the mounting of the resonance bars upon supporting straps through the medium of rubber or like grommets, said grommets and the bar supported thereby being so formed as to permit of only a knife-edge supporting contact therebetween. Such knife-edge contact serves to minimize the dampening of the tone, leaving the entire area of the bars exposed for vibration and thereby increasing the tonal volume of the bars which is desirable in a signal device of this character.

The full nature of the invention will be under-

2

stood from the accompanying drawings and the following description and claims:

Fig. 1 is a perspective view of the device showing the apertured housing cover.

Fig. 2 is a plan view of the interior of the device viewed from the back thereof with the dust cover removed.

Fig. 3 is a plan view showing the dust cover in relation to the exposed terminal plate.

Fig. 4 is a view taken on the line 4—4 of Fig. 2.

Fig. 5 is an enlarged view of a section through one of the grommets and the tonal bar carried thereby.

In the drawings there is shown a signal device 15 in the form of an electromagnetically actuated chime having a front housing cover 10 formed with walls 11 to embrace a resonance chamber. The upper and lower end walls are provided with ears 12 for convenient mounting of the device 20 upon a suitable support such as a vertical wall. Each of the side walls 11 have formed therein three apertures indicated at 13 intermediate the ends thereof and separated by the spacing bars 14, and the front wall is formed with inwardly 25 extending bosses 15 and 16.

The electromagnetic actuating unit 17 is provided with outwardly extending supporting feet 18 adapted to be secured to the bosses 15 through suitable rubber grommets. Said unit embodies 30 a pair of solenoids each having a plunger tube 19 in which the striking plungers 20 are actuated electromagnetically in the manner more particularly set forth and described in my application for Letters Patent, Serial No. 690,874, filed August 35 16, 1946, entitled "Electromagnetic device." The upper striking plunger is arranged for double action to strike the tonal bar 21 upon its solenoid being energized, and the tonal bar 22 upon being deenergized, as a result of spring action. The 40 lower striking plunger is single acting, striking the tonal bar 22 when the solenoid is energized and being snubbed when it is deenergized.

Said unit carries on the rear face thereof a terminal plate 23 having terminal connections 24 for 45 electrical connection with the electrical wiring 25. Said unit and tonal bars are sealed within the resonance chamber by a dust cover 26 clamped to the walls 11 by the ears 27, excepting for the exposure through the aperture 28 therein of the terminal plate 23. Thus, the electrical wiring 25 may be conveniently connected to the terminal plate without removing the dust cover which also protects the operative structure within the resonance chamber from interference thereby.

Mounted upon the bosses 16 there is a pair of

transversely arranged supporting straps 29, one above and one below the actuating unit. The ends of each of said straps are reduced at 30 and slightly rounded to receive a rubber grommet 31, said reduced ends 30 terminating in a bent over tip 32 for locking the respective grommets thereon. Said straps support the tonal bars 21, 22, the bar 21 being supported by the corresponding ends of said straps in position to be struck by the upper plunger 20. The bar 22 is supported by the corresponding opposite ends of said straps in position to be struck by either the upper or lower plungers 20. Said straps are arranged to support said bars inwardly a distance from their opposite ends approximately one quarter of their length so that about half the length of each bar spans the distance between their supporting straps 29. Said bars are also supported in spaced relation to the side walls 11 directly opposite the apertures 13, with said apertures arranged to span the central portion thereof.

For improving the tonal qualities and volume of the bars 21, 22, the grommets 31 are formed as shown in Fig. 5 to provide a knife-edge support, said bars as indicated at 33, having a circular aperture of an inner diameter less than the outer diameter of the opposed flanges of the grommets but greater than the inside diameter of said flanges. Said grommets may be of rubber or other flexible or resilient material such as to permit freedom of vibration of the bars relative to their fixed supporting straps, and furthermore, having a minimum of contact with said bars. Such mounting, by increasing the freedom of vibration correspondingly increases the tonal qualities and sound volume. Inasmuch as the major vibration of the bars is centrally thereof, the series of apertures 13 are positioned directly opposite thereto, permitting of ready passage and escape of the sound waves through the side walls of the cover with a minimum of interference.

From the above, it will be apparent that the two units of the operative structure may be conveniently mounted within the housing or removed therefrom if necessary, one comprising the electromagnetic actuating unit mounted upon the bosses 15, and the other comprising the tonal unit mounted upon the bosses 16. With said units mounted in place, and the dust guard 26 clamped to the housing, the operative structure need not be further disturbed in the mounting and wiring of the device for use.

Whereas, the invention has been disclosed herein in the form of one modification, it is obvious that variations thereof may be employed within the scope of the appended claims. For example, wherein the tonal bars are shown herein in of equal length but of different thickness to give off different tones, they may be of the same thickness but of different lengths in which case it is preferable to offset the straps 29 to accommodate such variation of length. Also, wherein said supporting straps 29 are shown herein as being independently mounted, they may be in the form of a supporting plate having projecting reduced strap portions 30 for supporting the tonal bars in the desired spaced relation relative to the striking plungers. Other variations in the structure over that herein shown can likewise be utilized without distinguishing from the invention as claimed. For example, wherein the apertures 13 are shown herein as grouped centrally of the side walls of the resonator chamber, they may be arranged in spaced relation so that the end portions of said walls are each provided with such

aperture to lie opposite each end of the respective tonal bars and thereby each utilizing a one quarter wave.

The invention claimed is:

1. A signal device comprising a front cover having walls thereabout embracing a resonance chamber, the side walls thereof being provided with a plurality of spaced apertures, inwardly extending bosses carried by said front cover, an electromagnetic actuating unit secured to one set of said bosses and provided with a pair of striking plungers, a pair of mounting straps secured to the other set of said bosses on opposite sides of said actuating unit, and spaced tonal bars carried by opposite ends of said straps positioned to be struck by said plungers, said bars extending parallel with and spaced from said walls opposite said apertures.

2. A signal device comprising a front cover having walls thereabout embracing a resonance chamber, inwardly extending bosses carried by said front cover, an electromagnetic actuating unit secured to one set of said bosses and provided with a pair of striking plungers, a pair of opposed tonal bars positioned to be struck by said plungers mounted on the other set of said bosses within the walls of said front cover, and a back cover for enclosing said units apertured to expose the wiring connections of said electromagnetic actuating unit.

3. A signal device including a support, a pair of spaced tonal bars, each bar having an aperture therein, a bracket on said support for mounting said bars, a grommet interposed between said bracket and each of said bars extending through the respective apertures therein, said bars being of a thickness and each of said grommets being formed with oppositely inclined flange portions embracing said apertures, said apertures of a diameter relative to the spacing and inclination of the flanges of said grommets for effecting a knife-edge supporting contact between said grommets and the opposed edges of the apertures in said bars.

4. A signal device including a support, a tonal bar adapted to be carried by said support, said bar being apertured, a yielding grommet mounted on said support extending through said aperture and formed with oppositely inclined flanged portions engageable with the opposite peripheral edges thereof for knife-edge supporting contact therewith whereby the inner surface of said aperture will be spaced therefrom.

5. A signal device including a support, mounting straps secured to said support, the opposite ends of said straps being reduced and terminating in a deformable interlocking tip, a resilient grommet mounted on each of said reduced ends and locked thereon by said tip, and a pair of opposed tonal bars apertured adjacent their opposite ends carried by the correspondingly reduced ends of said straps and embraced by said grommets within said apertures.

6. A signal device including a support, a pair of spaced mounting straps secured to said support, the opposite ends of said straps being reduced and terminating in a deformable interlocking tip, a resilient grommet mounted on each of said reduced ends and locked thereon by said tip, and a pair of opposed tonal bars apertured adjacent their opposite ends carried by the correspondingly reduced ends of said straps and embraced by said grommets within said apertures, the inner surface of said apertures being spaced from said grommets by a knife-edge contact be-

tween the opposite edges thereof and the inner
biased surfaces of said grommets.
